CLAIM

I claim the ornamental design for a toothpick, as shown and described.

DESCRIPTION

FIG. 1—is a perspective view of a toothpick showing my new ornamental design;

FIG. 2—is a side elevational view thereof, the other side being a mirror image;

FIG. 3—is a rear elevational view thereof;

FIG. 4—is a front elevational view thereof;

FIG. 5—is a top plan view thereof; and,

FIG. 6—is a bottom plan view thereof.
